CLAIM

The ornamental design for an electronic device, as shown and described.

DESCRIPTION

FIG. 1 is a top, front, right perspective view of an electronic device, showing our new design;

FIG. 2 is a bottom, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The electronic device of FIGS. 1-8 is intended, for example, to generate electric simulation signals for stimulating one or more anatomical structures, such as the spinal cord.

The broken lines of even length shown in the drawings illustrate portions of the electronic device that form no part of the claimed design.
